UNITED STATES PATENT OFFICE.

JAMES G. PENNYCUICK, OF TORONTO, CANADA, ASSIGNOR TO THE PRISMATIC GLASS COMPANY OF TORONTO, LIMITED, OF SAME PLACE.

DESIGN FOR A VAULT-LIGHT.

SPECIFICATION forming part of Design No. 25,573, dated June 2, 1896.

Application filed April 23, 1896. Serial No. 588,827. Term of patent 14 years.

To all whom it may concern:

Be it known that I, JAMES G. PENNYCUICK, a subject of the Queen of Great Britain, residing at Toronto, in the county of York and Province of Ontario, Canada, have invented and produced a new and original Design for Vault-Lights, of which the following is a specification, reference being had to the accompanying drawing.

10 My design is illustrated in the accompanying drawing, which represents a perspective view of my vault-light or tile.

15 The leading feature of my design consists in the prisms 1 2, one being of greater depth than the other, and the inclined sides of the shallower (indicated by 1) being substantially at an angle of forty-five degrees to the horizontal, while the other prism, 2, is substan-

tially at an angle of fifty degrees to the horizontal.

20 On the upper surface of the light or tile is a series of teats or projections 3, and around the edge is a rabbet 4, the corners 5 under the projecting flange 6 being slightly rounded, as shown by the shading.

25 What I claim as new is—

The design for a tile or vault-light, substantially as shown.

30 In testimony whereof I affix my signature, in the presence of two witnesses, this 22d day of April, 1896.

JAMES G. PENNYCUICK.
